OIL BURNER BAFFLE SYSTEM

Kenneth S. Jenson and Frederick W. Suhr, Wisconsin Rapids, Wis., assignors to Preway Inc., Wisconsin Rapids, Wis., a corporation of Wisconsin

Application October 22, 1948, Serial No. 55,956

10 Claims. (Cl. 158—91)

1 This invention relates to a system of baffles designed for use with a liquid fuel vaporizing pot type burner. The present improvements are concerned primarily with the baffle structure per se.

Pot type burners for vaporized liquid fuel operate normally with a flame which burns from and over a rich mixture of oil vapor and air which is present inside the pot. Proper operation requires that the vapor atmosphere be of such richness that ignition cannot take place except in the area where air is injected in sufficient quantity. The burning rate is controlled by varying the supply of liquid fuel. As more or less fuel is released into the burner, the depth of fuel vapor is raised or lowered; the base of the flame is likewise raised and lowered according to the depth of the fuel vapor. If the fuel control means be set to supply a minimum or low fire volume of fuel, any reduction in the fuel supply below that point will reduce the richness of the fuel vapor atmosphere to such an extent that improper combustion will take place and produce a smoky flame which burns directly from the surface of the oil pool on the burner bottom.

In most instances it is found that more heat than is desired is given off at the minimum or proper volume of fuel supply. To reduce excessive heat in such conditions a reduction of air supply and volume of fuel vapor atmosphere must be made. In the past this reduction of air and volume of fuel vapor atmosphere has been accomplished in various ways, but always with a reduction in burner performance.

One of the objects of our invention is to provide a burner having a wide range of combustion stages varying from a very small fire to an extremely large fire with a high degree of combustion efficiency maintained over the entire range. Another object is to provide means for guiding the combustible gas mixture in and about the burner uniformly prior to and during its combustion. Another object is to provide means for facilitating expansion and contraction of the fuel vapor atmosphere as more or less liquid fuel is supplied to the burner. Another object is to provide a pot type burner for vaporized liquid fuel in which these several objects are attained but with means to prevent air eddies from developing on one side of the burner, tending to cause the flame to decentralize and smoke.

Other objects attained by this invention include the provision of an elongated fixed passage-way for the rising burnable gas mixture; control of the rising burnable gas mixture vertically even where the distance between baffle plates is in-

2

creased beyond that where horizontal plates lose their effectiveness; for the rising gas a uniform control means which operates irrespective of the vertical spacing between segmental baffles by providing a tortuous passage from stage to stage between the baffles; means to insure a gradual rise of the flame from zone to zone without noticeably changing its general shape or character; a fixed passageway for the rising burnable gas mixture separate and distinct from a vertical opening which is provided centrally through the burner; a baffle structure which can be readily removed through a small heat drum door opening whenever repairs or cleaning are to be attended to; a baffle structure which will increase the heat output of the burner over that which is obtainable without such baffles; means for increasing the carbon dioxide percentage of the flue products at the maximum fire; baffle means which will permit reflected heat from above the flame to readily vaporize the fuel therebelow on the burner bottom; means to facilitate vaporizing and consumption of stable hydrocarbons, such as catalytically cracked fuel oil, without excessive accumulations of soot or carbon residue in the burner, or in the associated heat drum or flues; a baffle structure which is so designed as to prevent excessive warpage and sagging of any of its parts due to the intense heat present in the burner pot; and means for releasably uniting the baffle structure together in two half sections so that they can easily be separated for removal from or replacement within the pot burner without getting out of index with relation to each other.

With the above and other objects in view, our invention consists in the construction and novel combination and arrangement of parts herein-after fully described, illustrated in the accompanying drawings, and pointed out in the claims hereto appended, it being understood that various changes in the form, proportions, and minor details of construction, within the scope of the claims, may be resorted to without departing from the spirit or sacrificing any of the advantages of the invention.

In the drawings:

Figure 1 is a central vertical section through a drum wherein is operatively positioned a liquid fuel vaporizing pot type of burner equipped with the present baffle system;

Fig. 2 is a transverse section through the burner pot, taken just above the baffle structure therein; and

Figs. 3 and 4 are enlarged elevational and perspective views, respectively, each looking toward

the concave side of a different unit of the baffle structure.

As herein illustrated, an upright heating drum D carries in its upper region a shell 10 open at the bottom and at 11 upon one side thereof, the shell constituting a so-called economizer which is spaced from the vertical walls 12 of the drum. Near its bottom the drum is provided with a floor 13 and with depending feet 14 which, when rested upon a building floor, will support the drum slightly elevated whereby air may freely circulate thereunder. In its front wall we provide a lighting door 15 hinged at the bottom and provided near its top with a handle 16 in operative connection with a bolt whereby to secure the door in a normally closed position. A drum of this character is commonly enclosed within a cabinet (not shown) of ornamental character. Extending from the rear wall of the drum, and in communication with the interior thereof, is a flue pipe 17 leading to a chimney (not shown). The parts just described are more or less conventional at the present time, and have been adverted to mainly because it is with such a construction that the oil burner of our invention may advantageously be used.

The burner unit comprises a cylindrical pot P open at the top where it is provided with an outwardly flared flange 20 adapted to rest upon an angle ring 22 which is affixed to the interior of the drum, as by bolts. The pot thus suspended extends downwardly into the drum, spaced from its vertical walls 12; the pot bottom 23, which may be dished downwardly, is then maintained above the drum floor 13 a distance which is sufficient to permit a ready circulation of air through the intervening space. A substantially level sunken channel 24 may be extended radially in the bottom from about its center to a point at one side of the pot where connection is made with the inlet end of a fuel pipe 25 in communication with a constant level valve 26 to which fuel is fed from a supply source (not shown). By the provision of the channel 24 we obtain the advantage of locating the fuel pipe at the lowest possible point.

Near the burner top is a plurality of relatively large holes 27 inwardly slanted from above and arranged in a row circumferentially of the burner for admitting a secondary supply of air to the interior of the pot; the primary supply of air thereto is admitted through other holes circumferentially of the pot at lower elevations, five such rows 28, 29, 30, 31 and 32 being shown. The holes in the lowermost row are shown as inwardly slanted from below.

The features which are special to our invention are incorporated within a pot burner P of the general kind just described. These consist of a pair of baffle structure units each made up of semi-annular or segmental plates which may be three in number, designated as A, B, and C, and arranged in tiers vertically spaced from each other. These segmental plates in the two units comprise in each instance two complementary sections a, a', b, b', and c, c', each extending through substantially 180° so that, when positioned operatively with respect to each other, the sections a, a', b, b' and c, c' will each extend around within the pot for the full circumference thereof. Although the several baffles are much alike in their constructional features, the one which is lowermost, designated as C, is specifically different from the others and so will require separate description.

This lowermost baffle C is supported within the pot at a point which is elevated above its bottom 23. For this purpose a plurality of pins 35 are anchored to the vertical walls of the pot and extended radially thereinto for a short distance to provide points of support on which the baffle C may be loosely rested. Each section c, c' of this baffle comprises a plate 36 in the form of a semi-annulus (see Fig. 4) having flanges 37 upturned at its opposite ends to lie in substantially diametrical relation; its inner concave edge 38 is shown as rounded upwardly, and its outer convex edge may be arcuately notched at 39 for a slight radial distance at points which are intermediate of a pair of segmental ports 40 each of which extends inwardly from a line concentric with the outer edge of the baffle to a point that is relatively close to its rounded concave edge 38; and four radial walls 41 are struck down from the plate 36 along opposite edges of the two segmental ports 40. These walls 41 which lie in vertical planes constitute part of our improved baffle structure whose operation will be described in detail at a later point.

The intermediate baffle B comprises a plate 56 in the form of a semi-annulus whose inner concave edge 58 is reinforced by a bead, and whose outer convex edge may be arcuately notched at 59 for a slight radial distance at points which are offset with respect to a segmental port 60 which extends outwardly from a point relatively close to its concave inner edge; a pair of ports 57 one at each end of the plate 56 and opening radially thereupon; and four radial walls 61 along opposite edges of the segmental ports 60 and from the radial edges of the ports 57 as well. The rotative position of the port 60 is vertically misaligned with the segmental ports 40 and 50 of the baffles A and C. The walls 61 which lie in vertical planes constitute part of the improved baffle structure whose operation will be described in detail at a later point.

It will be noted that the three baffles each comprises two similar semi-annular or segmental sections, those of the lowermost baffle C being arranged on opposite sides of a common diametric line with their plates 36 engaging the pins 35 to be supported thereby. By reference to Fig. 2 it will be noted that six anchor pins are provided, arranged in two sets of three each symmetrically on opposite sides of the diametric line which separates the two sections c, c'; the positions of these pins are such as to clear the depending radial walls 41. The pins 35 provide a means of support for the two baffle units at an elevation such that the two semi-annular plates 36 of the lowermost baffle will lie in a horizontal plane intermediately of the two lowermost circumferential rows of holes 31 and 32 comprised in the primary air supply for the burner pot. To facilitate movement of the two baffle units into operative position and hold them in correct rotary index a pair of diametrically opposed fins 65 may be affixed to the vertical wall of the burner pot in positions to intervene between the sections, as best shown in Figs. 1 and 2. This index position for the baffle structure requires that the two fins 65 be located at points 180° apart and 90° from the fuel inlet pipe 25; in this position an unported area comprised in the lowermost baffle C will be disposed directly above the point of fuel inlet, and ported areas will be located to the side thereof at substantially equal distances.

Preliminary to insertion of the two baffle units

into the burner pot it will be found advantageous to preassemble the three sections *a*, *b*, and *c* into one unit, and the three sections *a'*, *b'*, and *c'* into a second unit. To do this, each set of three sections is arranged in the superposed relation best shown in Fig. 4 with the feet 53 of the legs 52 depending from the baffle A inserted through preformed slots in the plates 56 of the baffle B, the feet protruding a distance sufficient to permit of their being turned and clinched on the opposite sides (see Fig. 3); the feet 63 of the legs 62 depending from the baffle B are likewise inserted through preformed slots in the plates 36 of the baffle C, these feet being also protruded a distance sufficient to permit of their being turned and clinched on the opposite side. The positions of the slots through which the feet are inserted is such as to predetermine rotative settings of the baffles A and C in mutual alignment and of the intermediate baffle B in misalignment therewith.

Each unit of three baffle sections is next passed through the doorway in the front of the drum D to be placed through the open top of the pot into operative position therewithin. As has already been explained, the positions of the anchored pins 35 will predetermine the vertical position of the two sections of the lowermost baffle and thereby the other baffles which have been previously assembled therewith in unitary relation. The vertical spacing between the baffles is such that the semi-annular plates 56 of the baffle B will lie in a horizontal plane immediately of the circumferential rows of holes 30 and 31, and the semi-annular plates 46 of the baffle A will lie in a horizontal plane immediately of the circumferential rows of holes 28 and 29, all the holes comprised in these three rows forming a major part of the primary air supply for the burner pot. Because of the staggered rotative positioning of the three baffles, the segmental ports 60 of the baffle B will lie oppositely of and directly between unported areas of the semi-annular plates 36 and 46, and the unported areas of the semi-annular plates 56 will lie oppositely of and directly between the segmental ports 40 and 50. Likewise each pair of open ports 57 in the two semi-annular plates 56 of the intermediate baffle B will occupy confronting positions so as to constitute in each case a single segmental port similar to the port 60 but staggered with respect to the proximate segmental ports 50 and 40 in the baffles above and below. The ported and unported areas of the horizontal baffles and the vertical radially disposed walls thereof provide the tortuous passageway composed of vertical and horizontal portions and extending from the bottom to the top of the baffle structure and radially outset from the central vertical passageway.

The outside diameter of the three baffles is very slightly less than the inside of the burner pot P, leaving a clearance only sufficient for easy movement of each baffle unit into or out of the pot whenever the occasion may require. From this circumstance it follows that the elongated notches 39, 49 and 59 may be utilized to provide, in effect, arcuate ports staggered with respect to each other, but each aligned with a segmental notch (or notches) in an adjacent baffle (or baffles). To complete the assembly, an upwardly slanted flame ring, consisting of two coacting, semi-circular, separable segments 66 and 67, is fitted to the burner pot upon its top to reduce the circular opening at that point to an area of desired size.

A baffle means of the kind described, when installed in a pot burner, will convert poor or mediocre operation into performance which is outstandingly excellent. Several factors appear to be responsible. One of these is the spacing and positioning of the several baffles with respect to each other and to the primary and secondary air supplies for the burner; another is the size of the central openings and of the ports in the several baffles as well as the positioning of these ports with respect to each other; and still another is the provision and disposition of the radial walls depending into the spaces between the baffles at points adjacent the segmental ports therein. While satisfactory results may be obtained even when there is variation in these factors to some extent, we have demonstrated that superior performance will be assured with a burner whose pot has an inside diameter of about 11", when the diameter of the central opening in the lowermost baffle is about 4" (12.56 sq. in. in area) and the diameters of the central openings in the two baffles thereabove are about 5½" (23.76 sq. in. in area); when the spacing between the lowermost baffle and the pot bottom is about 3", when the spacing between the two lower baffles is about 1½" and the spacing between the two upper baffles is about 2¼"; when the unported area of each of the three baffle plates is about 45 sq. in., the ported area of the lowermost baffle being about 37 sq. in., and the ported area of each of the two upper baffles being about 26 sq. in.; and when each radial wall adjacent one edge of a segmental port depends therefrom for a distance of about ¾".

It will thus be seen that the area of the central opening in the lowermost baffle is approximately one-half that of each of the concentric openings in the baffles thereabove, that the spacing between the two lower baffles is approximately one-half that which obtains between the two upper baffles, that the ported area of the two upper baffles is about one-half that of its unported area, and that the ported area of the lowermost baffle is at least 50% greater than that of the others while its overall area is greater by only 15% or so. The supply of primary air entering into the space of double vertical distance between the two upper baffles is delivered through two rows of air inlet holes 29 and 33, and not just one such row as in the case of the lesser spacing between the two lower baffles.

In operation, the burning rate is controlled by the amount of liquid fuel which is supplied. For a minimum or low fire volume of fuel, all the air necessary for combustion below or at the low fire baffle C enters through the lowest row of primary air holes 32. At this stage the low fire baffle C serves to halt part of the down drafts from the upper portion of the pot which tend to disturb the balance of combustion in the space below this baffle. As a consequence, a low flame may be maintained under such conditions with a minimum release of free carbon.

In previous baffle systems it has been common to control the down draft air eddies in the burner pot by solid low fire baffles each having a single central opening therethrough for escape of the flame and combustion products, or having peripheral perforations or notches for this purpose. Baffle arrangements of these kinds have the disadvantage that sharp changes in the flame shape are produced, tending to upset the combustion from one level to the next. Stepped or staggered baffles have also been suggested, but these require

spacing which is too far apart, and also allow too much circulation in the pot for the maintenance of a good low fire. Placing of the top baffles closer together, as herein described, causes the high fire rate to be lowered or choked off before sufficient control is obtained of the air eddies; we find it expedient, therefore, to use the downturned radial walls adjacent the ported areas of the baffles to control the amount of fuel vapor which tends to ascend therethrough. A fixed distance is maintained between the baffles by the legs depending from the radial walls for connection with the next lower baffle. The baffle structure in its entirety is suspended vertically in spaced relation to the burner bottom 23 and above the lowermost primary air inlets 32, as by means of supporting pins 35 which are anchored to the burner walls. The baffle assemblies are held in rotary index with the fuel inlet pipe 25 by the vertical spacing fins 65. It is important for low fire operation that the lowermost baffle C be so positioned rotatively that an unported area of its body be located over the inlet point of the oil supply. The term "ported area," wherever used, refers to the area of one or more of the ports 40, 50, 57, and 60, and has no reference to the vertical passageway through the system formed by the central openings of the baffles.

In normal operation, oil is fed through the control valve and fuel line into the burner at a point adjacent its bottom. Upon ignition, the flame burns from the surface of the oil pool on the bottom until the rate of generation of fuel vapor increases to the point that burning directly from the pool surface is prevented by reason of an increased enrichment of the oil vapor. The flame then rises above the burner bottom 23, and generation of the fuel vapor is then produced from the heat reflected from the flame above. Combustion continues at a rate which is commensurate with the feed of oil into the burner, and so long as the rate of oil feed is kept below certain limits, or in proper relation to the supply of air entering through the lowermost inlet holes 32, the base of the flame will stay below the lower baffle C. When more fuel is added, the base flame will then rise to the higher rows of air inlet holes because the volume of the rich mixture of oil vapor and air in the lower portion of the burner has then increased substantially. When high fire has been reached, the flame base is at the level of the row of secondary air inlet holes 27, and while at this point the rate of fuel admitted into the burner can be increased until the flame starts to smoke. At this point maximum capacity will have been reached.

As the flame leaves the burner through the center aperture of the flame ring at the top, it radiates heat to the side walls of the drum D. The flame and hot gases will also enter the economizer 10 through its open bottom to impinge the top of the heat drum and then leave the economizer through the lateral opening 11 at the front thereof for circulation in the surrounding space interiorly of the heat drum D. Eventually the hot gases will discharge into the chimney through the flue passage 17. Because of this manner of operation the flame and hot gases are forced to give up their heat.

If it becomes necessary or desirable to clean out or repair the burner, each unit of the baffle structure may be independently removed through the lighting door 15 at the front of the drum. This is true even though the diameter of each baffle unit be larger than the door opening, due to each unit comprising but one of the two sections of

the several baffles. This is a marked advantage because it permits use of a smaller combustion door than would otherwise be required, thereby obviating the tendency of a larger door to warp and produce leaks with consequent reduction in the efficiency of the heater.

We claim:

1. In combination with a pot-type burner having means for supplying thereto liquid fuel in a controlled amount, the burner wall being cylindrical and provided with primary air inlet holes arranged in a plurality of circumferential rows, a system of interconnected superposed horizontal baffles in the burner, spaced apart vertically to position each baffle between two rows of inlet holes, each baffle having a central opening to define a vertical passageway through the system, said horizontal baffles being provided with openings and having vertical walls located at opposite edges of the openings and disposed transversely of the baffles, the openings of said baffles forming ported areas, the openings in each baffle being staggered vertically with respect to the openings of adjacent baffles, and the area of the central opening in the lowermost baffle being approximately one-half that in the baffle next above.
2. In combination with a pot-type burner having means for supplying thereto liquid fuel in a controlled amount, the burner wall being cylindrical and provided with primary air inlet holes arranged in a plurality of circumferential rows, a system of interconnected superposed horizontal baffles in the burner, spaced apart vertically to position each baffle between two rows of inlet holes, each baffle having a central opening to define a vertical passageway through the system, said horizontal baffles being provided with openings and having vertical walls located at opposite edges of the openings and disposed transversely of the baffles, the openings of said baffles forming ported areas, the openings in each baffle being staggered vertically with respect to the openings of adjacent baffles, and the ported area of the lowermost baffle being greater by at least fifty per cent than the ported area of the baffle next above.
3. In combination with a pot-type burner having means for supplying thereto liquid fuel in a controlled amount, the burner wall being cylindrical and provided with primary air inlet holes arranged in plural circumferential rows, a system of three interconnected superposed baffles in the burner, spaced apart vertically to position each baffle between two rows of inlet holes, each baffle having a central opening to define a vertical passageway through the system, the area of the central opening of the lowermost baffle being approximately one-half that in each of the others thereabove.
4. In combination with a pot-type burner having means for supplying thereto liquid fuel in a controlled amount, the burner wall being provided with primary air inlet holes arranged in a plurality of circumferential rows, a system of interconnected superposed baffles in the burner, spaced apart vertically to position each baffle between two rows of inlet holes, each baffle having a central opening to define a vertical passageway through the system, the area of the central opening in the lowermost baffle being approximately one-half that in the baffle next above and said baffles having openings forming ported areas staggered vertically with respect to one another and forming tortuous passageways spaced from the central passageway.

5. In combination with a pot-type burner having means for supplying thereto liquid fuel in a controlled amount, the burner wall being provided with primary air inlet holes arranged in a plurality of circumferential rows, a baffle structure comprising a plurality of interconnected superposed baffles in the burner, spaced apart vertically to position each baffle between two rows of inlet holes, each baffle having a central opening to define a vertical passageway through the structure, said baffles having openings forming ported areas and staggered vertically with respect to one another and forming tortuous passageways spaced radially from the central passageway, the ported area of the lowermost baffle being substantially greater than the ported area of the baffle next above and the ported area of the next to the lowermost baffle being substantially less than its total area, said structure consisting of two complementary units separated vertically in a plane diametrically of the burner, each unit being movable independently into and out of the burner.

6. In combination with a pot-type burner having means for supplying thereto liquid fuel in a controlled amount, the burner wall being provided with primary air inlet holes arranged in a plurality of circumferential rows, a system of interconnected superposed baffles in the burner, at least three in number, spaced apart vertically to position each baffle between two rows of inlet holes, each baffle having a central opening to define a vertical passageway through the system and the area of the central opening in the lowermost baffle being approximately one-half that in each of the others thereabove, said baffles having other openings forming ported areas and staggered vertically with respect to one another and forming tortuous passageways spaced radially from the central passageway.

7. In combination with a pot-type burner having means for supplying thereto liquid fuel in a controlled amount, the burner wall being provided with primary air inlet holes arranged in a plurality of circumferential rows, a baffle structure in the burner comprising interconnected superposed baffles, at least three in number, spaced apart vertically to position each baffle between two rows of inlet holes, each baffle having a central opening to define a vertical passageway through the structure and the area of the central opening in the lowermost baffle being substantially less than that of each of the others thereabove, baffles having other openings staggered vertically with respect to one another and forming ported areas and providing tortuous passageways spaced radially from the central passageway, said baffle structure consisting of two complementary units separated vertically in a plane diametrically of the burner, each unit being independently movable into and out of the burner.

8. In combination with a pot-type burner having means for supplying thereto liquid fuel in a controlled amount, the burner wall being provided with primary air inlets arranged in plural circumferential rows, a system of three interconnected superposed annular baffles in the burner, spaced apart vertically to position each baffle between two rows of inlet holes and provided with aligned central openings defining a vertical passageway, said baffles being provided with staggered openings forming ported areas and each

baffle having a plurality of said ported areas vertically staggered with respect to those in the next adjacent baffle forming a tortuous passageway spaced radially from the central vertical passageway, and means adjacent the ported areas of the baffles for retarding movement of vapors ascending through the baffle system, the distance between the two lowermost baffles being approximately one-half the distance between the two upper baffles.

9. In combination with a pot-type burner having means for supplying thereto liquid fuel in a controlled amount, the burner wall being provided with primary air inlet holes arranged in a plurality of circumferential rows, a system of superposed annular baffles in the burner, spaced apart vertically to position each baffle between two rows of inlet holes and provided with central aligned openings forming a central vertical passageway, said baffles being provided with staggered openings forming ported areas and each baffle having a plurality of said ported areas vertically staggered with respect to those in the next adjacent baffle, and radially extending walls depending from each baffle at points adjacent opposite sides of the ported areas, the openings and the radial walls forming tortuous passageways composed of vertical and horizontal portions and spaced from the central vertical passageway the distance between the two lowermost baffles being approximately one-half the distance between the two uppermost baffles.

10. In combination with a pot type burner having means for supplying thereto liquid fuel in a controlled amount, the burner wall being provided with primary air inlet holes arranged in a plurality of circumferential rows, a system of superposed annular baffles in the burner, spaced apart vertically to position each baffle between two rows of inlet holes and provided with central aligned openings forming a central vertical passageway, said baffles being provided with staggered openings forming ported areas and each baffle having a plurality of said ported areas vertically staggered with respect to those in the next adjacent baffle, and radially extending walls depending from each baffle at points adjacent opposite sides of the ported areas, the openings and the radial walls forming tortuous passageways composed of vertical and horizontal portions and spaced from the central vertical passageway the distance between the two lower baffles being approximately one-half the distance between the two upper baffles, and the depending distance of the radial walls being less than half the spacing between the two upper baffles and more than half the spacing between the two lower baffles.
